UNITED STATES PATENT OFFICE.

CHARLES HERBERT SCOTT, OF GLOUCESTER, ENGLAND.

MACHINERY FOR THE MANUFACTURE OF INLAID LINOLEUM.

SPECIFICATION forming part of Letters Patent No. 697,551, dated April 15, 1902.

Application filed May 1, 1901. Serial No. 58,281. (No model.)

To all whom it may concern:

Be it known that I, CHARLES HERBERT SCOTT, a subject of the King of Great Britain and Ireland, residing at Gloucester, in the county of Gloucester, England, have invented Improvements in the Manufacture of Inlaid Linoleum and in Machinery or Apparatus Therefor, of which the following is a specification.

10 This invention relates to the manufacture of inlaid linoleum, particularly that of the kind in which the pattern or design consists of small figures—for instance, squares of different colors and arranged so as to produce 15 the required effect—and to machinery or apparatus for use in such manufacture.

According to this invention a mixture of loose granulated linoleum is compressed during passage through a die into pieces of the required size and shape, which pieces as they are discharged from the die are pressed onto a canvas or other backing, and for the purpose of enabling a great variety of patterns or designs to be produced at small expense 25 the action of devices designed to effect the distribution from the supply-hoppers of the granulated linoleum of which the pattern is to be formed is regulated or controlled by pin or tappet drums, bands, or the like, or by 30 drums, bands, or the like formed with perforations or slots, the pins or tappets or the like or the perforations or slots or the like being arranged or disposed according to the pattern or design to be produced, the drums, 35 bands, or the like being capable of being changed or shifted when it is desired to alter the pattern or design produced, and the arrangement being such that only such material as is required for forming the pattern 40 or design will be distributed from the supply-hoppers.

Machinery or apparatus according to this invention may be variously modified.

The accompanying drawings illustrate, by way of example, one arrangement of machine, Figure 1 being a longitudinal section, Fig. 2 an end view of the lower part of same, and Figs. 3, 4, and 5 are detail views hereinafter referred to.

50 In the frame 1 of the machine are mounted a pair of shafts 2 2^a, each carrying a drum 3. Around these drums passes an endless band

4, that serves to support the canvas backing 5, onto which the pieces of linoleum are pressed. The shaft 2 has fixed to it a ratchet-wheel 6, which has a step-by-step motion imparted to it by a pawl 7, which is carried by an arm 8, turning about the shaft 2 and linked to a lever 9, carrying an abutment or roller 10, which is acted upon by a cam 11 on the main 60 shaft 12 of the machine. The endless band, with the canvas backing stretched on it, passes under a number of die-plates 13, one of which is shown in longitudinal and transverse vertical section in Figs. 3 and 4. In 65 the example illustrated there are two such die-plates; but there may be more than two. The upper part of each die-plate 13 is formed with a number of grooves or channels 14, which are of slightly-less width than the 70 squares or other figures in the pattern and may conveniently be horizontal. Above each die-plate is a hopper 15, adapted to contain granulated linoleum and to deliver the same to the several grooves or channels in the die-plate at or about the middle of their length. 75 The grooves are toward one end covered by a heated plate 16. The plate may be made with a passage 16^a, through which steam or hot air is passed or in which gas-burners 80 may be arranged. Each groove or channel 14 is fitted with a plunger 17, retained in position by a cover-plate 18, common to the set of grooves.

In connection with each die-plate 13 a transverse bar 19 is arranged so as to be capable of a parallel to-and-fro movement along the frame of the machine. The movement of this bar may conveniently be obtained by connecting it by links 20 to a lever or levers 21, 85 which is or are oscillated by a cam or cams 22 on the main shaft 12. The front edge of the bar 19 extends beneath the projecting ends of the plungers 17, each of which is formed with a downwardly-extending lug or hook 17^a, 95 adapted to engage with a shallow flange or lip 19^a, formed along the front of the transverse bar, the arrangement being such that during the backward movement of the bar 19 any plunger engaged by such lip will be drawn 100 back therewith. The rear portion 19^b of said bar is extended upwardly and carries or has pivoted or hinged to it a series of abutment-pieces 23, one of which is opposite to each

plunger. When these abutment-pieces are in their operative positions and the transverse bar 19 is moved to and fro, their respective plungers will also be moved to and 5 fro and will at each inward stroke discharge from the grooves or channels 14 certain quantities of linoleum mixture, while at each outward stroke fresh supplies of mixture will drop from the hoppers 15 into the grooves or 10 channels 14. When the abutment-pieces 23 are raised into their inoperative positions, the plungers will be left at the ends of their outward strokes and no mixture will be discharged from their grooves.

15 For the purpose of bringing the several abutment-pieces 23 into or keeping them out of action during the forward stroke of the transverse abutment-bar 19 in the order necessary for the production of the required pattern or design each abutment-piece 23 is connected, by means of a link or rod 24, to one end of a lever 25, the other end of which has a metal pin or point 26 working against a pattern-drum 27, formed of or covered with sheet 20 metal or other substance having perforations, 25 slots, or holes 28, Fig. 5, punched through it. This drum has an intermittent rotary motion imparted to it from the main or cam shaft 12 of the machine at those periods when the 30 transverse abutment-bar 19 is at rest in its rear position. In the example illustrated it is shown driven by belt-gearing from the shaft 2. Just before the drum is moved a kicker-bar 29, extending across beneath all the levers 25, actuates them in such wise as to free 35 their points 26 from the perforations, slots, or holes 28 in the pattern-drum, the kicker-bar 29 again moving after the drum has moved so as to allow the points 26 of the 40 respective levers to rest on the surface of the pattern-drum and so hold their abutment-pieces out of action or to enter the perforation, holes, or slots and allow their abutment-pieces to come into action, according to the 45 pattern to be produced. Across the front end of the grooves there is formed through the die-plate 13 a slot 30, which serves as a delivery, whence the linoleum mixture discharged from the grooves or channels 14 is 50 deposited onto the canvas backing 5, passing beneath it. Within this slot is fitted a pressure plate or plates 31, which is or are reciprocated vertically by means of bell-crank levers 32, to which it or they is or are connected 55 and which are linked to a lever 33, oscillated by a cam or cams on the main or cam shaft 12. The pressure plate or plates is or are arranged and actuated so that during a portion of the forward stroke of the abutment-bar 19 they 60 close the outlet ends of the grooves or channels 14, is or are then raised, so as to allow of the mixture being discharged from the said grooves or channels into the delivery-slot 30, and is or are then moved down again, 65 so as to force out the mixture onto the canvas backing beneath. The delivery-slot may

be continuous for the whole width of the machine; but it can be divided into vertical grooves, the number of which corresponds to or is a multiple of the number of grooves or 70 channels 14 in the die-plate. The thickness or width of the delivery-slot and pressure plate or plates is slightly less than the length of the squares or other figures forming the pattern.

75 Each supply - hopper is provided with a shaking-bar 34, with arms 35, adapted to shake the loose granulated linoleum into the grooves or channels in the die-plates.

75 The action of the machine is as follows: Assuming that all the plungers 17 are in their outermost positions, the action of the shakers 35 causes the horizontal grooves or channels 14 in the die-plate to be charged with granulated linoleum. The abutment-bar 19 now travels 85 forward and with it such of the plungers 17 as have their abutment-pieces 23 in the operative or lower position, which plungers compress the linoleum into those portions of the grooves or channels 14 in the die-plate which 90 are beneath the heated plate 16, the pressure plate or plates 31 preventing for the time being the discharge of the linoleum from said grooves or channels. The forward movement of the abutment-bar 19 then ceases and the 95 pressure plate or plates 31 is or are lifted, leaving the ends of the grooves or channels 14 open, whereupon the abutment-bar advances, pushing the compressed linoleum out of the 100 grooves into the delivery-slot 30 and beneath the pressure plate or plates, which then descends or descend rapidly and pushes or push the compressed pieces of linoleum out of the delivery-slot onto the canvas backing 5 below. The abutment-bar 19 then travels back, 105 the flange or lip 19^a along its front edge engaging with and drawing back the plungers 17 to their original position, the kicker-bar 29 lifts all the points 26 clear of the pattern-drum 27, whereupon the pattern - drum is 110 partly rotated, so as to present a fresh row or series of perforations, holes, or slots 28 to the levers. This operation is repeated, the canvas backing 5 moving forward step by step and the plungers 17, which are moved forward at each forward stroke of the abutment-bar 19, being varied in accordance with the varied disposition of the perforations, holes, or slots in that part of the drum which is for 115 the time presented to the abutment-levers. 120 Whenever a perforation, hole, or slot 28 in the drum 27 comes opposite the point 26 of the lever 25 of a given abutment-piece 23, that particular piece will drop into its operative position and the corresponding plunger 125 17 will travel forward and push a compressed piece of linoleum under the pressure-plate 31, which deposits it onto the canvas backing.

130 The patterns can be changed by changing the perforated sheet-metal covering of the drum or by changing the drum itself.

The canvas backing may, in some cases, be

caused to travel continuously at such a speed as will permit of the linoleum being properly deposited upon it.

Instead of the drum flat sheets of metal traveling in a horizontal, vertical, or other convenient direction can be used. Also the drums, sheets, or the like may be provided with pins, knobs, or tappets adapted to bring the plungers into action or hold them out of action.

As will be understood, there may be any desired number of grooved or channeled die-plates with appurtenances, each being provided with a hopper for containing a different-colored linoleum, the number or variety of patterns or designs which the machine can produce varying accordingly. The several die-plates are fixed one behind the other upon the machine, and the several abutment-bars are connected together by links 36 and operated simultaneously.

In some cases some or each of the hoppers may be divided into compartments, each of which can be charged with a different-colored linoleum.

What I claim is—

1. In apparatus for the manufacture of inlaid linoleum, the combination of a die, means for supplying linoleum mixture thereto, a transverse discharge-passage in communication with said die, and means for compressing the mixture within the die into a piece of the required size and shape and discharging it from said die into said passage, as set forth.

2. In apparatus for the manufacture of inlaid linoleum, the combination of a die, means for supplying linoleum mixture thereto, a transverse discharge-passage in communication with said die, means for supporting a traveling backing beneath said passage and means for compressing the material within the die into a piece of the required size and shape and discharging the compressed piece from the die into the discharge-passage and onto said backing, as set forth.

3. In apparatus for the manufacture of inlaid linoleum, the combination of a transverse row of dies, means for supplying linoleum mixture thereto, means for compressing the mixture within the dies into pieces of the required sizes and shapes, a transverse discharge-passage in communication with said dies, and means for discharging the compressed pieces, as set forth.

4. In apparatus for the manufacture of inlaid linoleum, the combination of a number of transversely-arranged rows of dies, means for supplying linoleum mixture thereto, plungers therein adapted to compress the mixture into pieces of the required size and shape against transversely-movable plates that normally close said dies, means for withdrawing said plates and means for discharging the compressed pieces, as set forth.

5. In apparatus for the manufacture of inlaid linoleum, the combination of a series of

dies, means for supplying linoleum mixture thereto, compressing-plungers therein, transverse discharge-passages communicating with the outlets from said dies, pressure-plates located in said discharge-passages and adapted to close the outlet ends of the dies, means for reciprocating said plungers at the required times and means adapted to move said pressure-plates clear of the outlets of the dies after part of the forward movement of the plungers has occurred, and to reversely move said pressure-plates after the plungers have completed their forward movements and then discharge the compressed mixture, substantially as described.

6. In apparatus for the manufacture of inlaid linoleum, the combination of a series of dies, means for supplying linoleum mixture thereto, compressing-plungers therein, transverse discharge-passages communicating with the outlets from said dies, pressure-plates located in said discharge-passages and adapted to close the outlet ends of the dies, a bar extending across the ends of said plungers, means for moving said bar toward and from said dies, an abutment-piece opposite the outer end of each plunger and carried by said bar and each capable of being separately moved into and out of engagement with its plunger, means adapted to move said pressure-plates at the required times, as set forth.

7. In apparatus for the manufacture of inlaid linoleum, the combination of a series of dies, means for supplying linoleum mixture thereto, a series of compressing-plungers, one in each die, means for reciprocating said plungers and pattern-controlling means whereby the reciprocating means of the several plungers are held in and out of their operative attitude in the required order, as set forth.

8. In apparatus for the manufacture of inlaid linoleum, the combination of a series of dies, means for supplying linoleum mixture thereto, a transverse discharge-passage in communication with said dies, plungers in said dies adapted to compress the mixture into pieces of the required size and shape, and a movable device having a surface of a particular contour adapted to control the reciprocating means of the several plungers, as set forth.

9. In apparatus for the manufacture of inlaid linoleum, the combination of a die-plate 13 having a series of grooves 14, hopper 15, plungers 17 having hooks 17^a, transverse bar 19 with lip 19^a, means for moving said bar to and fro, abutment-pieces 23, a movable device having perforations, pins or points 26 resting against said device, means connecting said pins or points 26 to said abutment-pieces 23 and a kicker-bar 29, as set forth.

10. In apparatus for the manufacture of inlaid linoleum, the combination of a grooved die-plate 13, hopper 15, heated plate 16, plungers 17, transverse bar 19, links 20, levers 21, cam 22, abutment-pieces 23, links 24, levers 25 having pins or points 26, perforated drum

27, means for moving said drum at the required times, and kicker-bar 29, as set forth.

11. In apparatus for the manufacture of inlaid linoleum, the combination of a series of dies, means for supplying linoleum mixture thereto, compressing-plungers therein, transverse discharge-passages communicating with the outlets from said dies, pressure-plates located in said discharge-passages and connected to bell-cranks, links connecting said bell-cranks to levers moved at the required times by cams, as set forth.

12. In apparatus for the manufacture of inlaid linoleum, the combination of dies, means for supplying linoleum mixture thereto,

means for compressing into pieces the mixture therein, transverse discharge-passages communicating with the outlets of said dies, means for supporting and intermittently moving a traveling backing beneath said discharge-passages and means for discharging the compressed pieces from said dies and discharge-passages onto said backing as set forth. 20

Signed at Gloucester this 16th day of April, 1901.

CHARLES HERBERT SCOTT.
